Primary Examiner — Barbara Fox*Assistant Examiner* — Dana K Weiland(74) *Attorney, Agent, or Firm* — Mitchell Law PLLC;
 Matthew W. Mitchell(57) **CLAIM**

The ornamental design for a mobile computing device, as shown and described.

DESCRIPTION

FIG. 1 is a front isometric view of the mobile device showing the new design;

FIG. 2 is a second front isometric view of the mobile computing device of FIG. 1;

FIG. 3 is a back isometric view of the mobile computing device of FIG. 1;

FIG. 4 is a top view in elevation of the mobile computing device of FIG. 1;

FIG. 5 is a bottom view of the mobile computing device of FIG. 1; and,

FIG. 6 is the side view of the mobile computing device of FIG. 1, the other side views being identical.

The broken lines shown in the drawings depict portions of the mobile computing device that form no part of the claimed design.

1 Claim, 6 Drawing Sheets(56)
